Specification for Design.

Patented June 25, 1912.

Application filed December 16, 1911. Serial No. 666,268. Term of patent 7 years.

To all whom it may concern:

Be it known that I, FREDERICK B. MALLORY, a citizen of the United States, residing at Portland, in the county of Multnomah and State of Oregon, have invented a new, original, and ornamental Design for Guards for Pulleys, of which the following is a specification.

In order to fully comprehend my invention reference must be had to the accompanying drawing in which,

Figure 1 is a front elevation of my invention and Fig. 2 is a side elevation of same.

I claim:

The ornamental design for guard for pulley as shown.

In testimony that I claim the foregoing as my own, I hereunto affix my signature in the presence of two witnesses.

F. B. MALLORY.
